UNITED STATES PATENT OFFICE.

CARL WINKLER, OF BERN, SWITZERLAND.

PRODUCTION OF STEREOTYPIC PRINTING-PLATES.

1,204,107.

Specification of Letters Patent.

Patented Nov. 7, 1916.

Application filed February 25, 1915. Serial No. 10,598.

To all whom it may concern:

Be it known that I, CARL WINKLER, a citizen of the Swiss Republic, residing at Bern, in the Swiss Republic, have invented new and useful Improvements in the Production of Stereotyped Printing-Plates, of which the following is a specification.

Heretofore it was usual, in casting stereotyped printing plates, to heat the mold to a temperature of about 150° C. before casting. On pouring in the molten lead having a temperature of about 300° C. the mold was naturally still further heated by this metal, and it was then soon cooled down again by cold water. As a consequence the mold was subjected to many considerable changes, which necessarily had a bad influence on the plate being cast. Further, it was usual to treat both parts of the mold, that is the part carrying the matrix and the part forming the back of the plate, uniformly, by causing cooling water of the same temperature to pass through said parts.

Now, in order to produce plates characterized by greater accuracy and reliability than those heretofore used, the parts of the mold are separately treated according to the present invention, and indeed in such a manner that the temperature of each part separately is kept as uniform as possible during the entire casting process. For example, the part carrying the matrix (thus in the case of curved plates mostly the cope or bed) is to be kept permanently at a temperature of about 150° C., and the other part at about 100° C., during the entire process. Trial has shown that plates produced under these conditions are much more accurate than those produced heretofore, so that such plates are particularly suitable for multiple color printing.

For heating the parts of the mold, steam will be found suitable, which may be caused to circulate through channels specially provided for the purpose. This steam, therefore, does not only serve to heat the mold, but also to prevent said mold from getting hotter when the molten metal is poured in, the steam taking up and carrying off all such excess heat.

Instead of steam any other suitable agent, such as hot water, air, gas, oil, or the like, may be employed.

If steam is used for heating the mold the apparatus shown on the drawing may be used with advantage. In this apparatus

the waste gases of the furnace used to melt the stereotype metal are adapted to heat a boiler.

In the drawing a sectional elevation of the apparatus is shown.

The metal to be melted is contained in the crucible *a*, which is heated by the fire on the grate *b*. The hot gases leave the furnace through the opening *c* and pass into the steam generator *d*, where they pass through the pipes contained therein and finally escape through the flue *e* or the like. The lead fumes from the crucible are led off through the hood *f* and pipe *g* to the flue *e*.

A door *i* is hinged to swing against the lower ends of the pipes of the generator as shown in dotted lines and when in this position the gases passing off from the furnace are caused to pass through a jacket provided between an outside mantle and the boiler instead of through the whole boiler itself. In this case no steam is developed, but the water contained in the boiler is only heated somewhat. The steam generated in the boiler *d* is conducted through the pipe *h* having a cock *k* to a steam chamber *l* in the bed of the mold. The full pressure of the steam acts in the steam chamber and as a consequence a temperature corresponding to the pressure, for example about 150 degrees C., is maintained in the bed. A branch pipe *i* leads from the pipe *h* to a chamber of the drag 2 of the mold, and in said branch pipe is a throttling valve *n* which reduces the pressure of the steam to about atmospheric pressure and the steam at this pressure enters the chamber of the drag, and is maintained therein at about 100 degrees C.

Over the boiler there is a water receiver *h* which is arranged in such a way that in every position of the door *i* it is always heated by the gases passing off from the furnace. This hot water can be used for one or both parts of the mold.

When the door *i* is open the gases pass from the grate *b* through the opening *c* and simultaneously through the pipes *d* and between the boiler and the outer casing. As the space between the boiler and the outer mantle is narrow, and as the top of this space is not open all around, but only for a part of its circumference, there is some little resistance to the passage of the gases so that these gases also descend somewhat after passing through the opening *c* and escape into the pipes *d* in which there is also a

draft. If the door *i* is closed it is evident that the gases cannot enter the pipes *d*, but can only pass between the boiler and the outer mantle; the jacket, although not necessarily open all around, is at least provided with openings to enable the products of combustion to pass through.

The grate in the fire-box in which the door *i* swings may be adapted to be taken out in 10 order to enable the door to be closed.

It is to be understood that the temperatures given above are not binding, but are only to be considered as examples.

What I claim and desire to secure by Letters Patent of the United States is:—

1. The process for casting stereotype plates which consists in keeping the parts of the mold at approximately constant but different temperatures during the time immediately preceding the flowing in of the molten metal, during the flowing in of the molten metal and during the cooling of the

plate, by conducting a thermic agent of higher constant temperature through the jacket of the part carrying the matrix and a 25 thermic agent of lower constant temperature through the other part of the mold, substantially as and for the purpose set forth.

2. The process of casting stereotype plates, consisting in subjecting the parts of the mold, prior to the introduction of the metal thereto, to the action of a heating medium to raise the part carrying the matrix to a temperature greater than the other part, and maintaining the parts of 30 the mold at constant but different temperatures throughout the casting operation.

In testimony whereof I have signed my name to this specification in the presence of two subscribing witnesses.

CARL WINKLER.
